A jointed gauge wire is disclosed for use in the weaving of textile fabrics. The gauge wire is composed of a stationary section which is woven into the fabric, and a movable section which extends rearwardly from the fabric. The movable section is pivotally connected to the stationary section, and is also pivotally connected to a rigid anchor bar which is secured to the rear of the heddle wire.

PILE GAUGE

Julius A. Goetz, Philadelphia, Pa., assignor to
John Zimmerman & Sons, Incorporated, Phila-
delphia, Pa., a corporation of Pennsylvania

Application August 15, 1939, Serial No. 290,321

4 Claims. (Cl. 139—37)

This invention relates to jointed gauge wires for use in the weaving of textile fabrics, wherein a plurality of such wires are interspersed among the warp threads in a loom and extend substantially parallel thereto in that portion of the woven fabric lying adjacent and forward of the fell, and along those portions of the warp threads extending rearwardly from the fell.

The invention is applicable to looms employing single or double shuttles, in the weaving of single fabrics, double fabrics connected by pile warps, or two separate fabrics with their respective pile warps in interposed relation, with the gauge wires woven into the single fabric or interposed between the two connected fabrics, or respectively woven into both the separate fabrics, for determining the length of the cut or uncut pile tufts or loops, in accordance with the character of the finished fabric desired.

It is common practice, in weaving, to use jointed gauge wires, and to weave one section of each wire into that portion of the fabric lying at and adjacent the fell, with another section of each wire pivoted, end to end, to the woven-in section, at the fell, and extending rearwardly therefrom, to rise and fall with selected warp threads for forming open warp sheds to receive weft threads carried through the open warp sheds by shuttles operating transversely to the warps. As the weaving of the fabric progresses, pick by pick, the woven-in ends of the gauge wires are slipped rearwardly within the fabric accordingly, i. e. the fabric is intermittently woven off or drawn off the free ends of the wires by the take-up mechanism of the loom. In order to slip the free ends of the woven-in sections of the gauge wires in the fabric, the opposite ends of the wires heretofore have been pivotally attached to the heddle wires, by which the movable sections of the gauge wires which extend rearwardly from the fell are raised and lowered in the shed forming operations. This places the heddle wires under severe lateral or transverse strain and frequently causes breakage or permanent distortion thereof. Such distortion has a detrimental effect on the weaving of perfect fabric and requires frequent stoppages for replacement with a consequent loss of production.

The object of the present invention is to relieve the heddle wires of the transverse strains attending the slipping of the woven-in sections of the gauge wires in the fabric in opposition to the operation of the take-up mechanism of the loom. This object is attained by eliminating the fixed pivotal connection between the heddle

wire and the movable section of the gauge wire, extending the gauge wire through an eye formed in the heddle wire to a point beyond the rear of the heddle wire, adding a third section to each gauge wire, and forming a connection thereby between the rear end of the movable section of the gauge wire and a rigid anchorage located behind and remote to the rear of the heddle wires.

A gauge wire constructed in accordance with the principles of the present invention will be fully disclosed hereinafter, reference being had to the accompanying drawing, of which:

Fig. 1 is a perspective view of sufficient of the gauge wire and the cooperating heddle wire to illustrate the construction of each thereof;

Fig. 2 is a diagrammatic longitudinal sectional view of a portion of a loom of the double shuttle type illustrating a pair of gauge wires constructed in accordance with the principles of the present invention;

Fig. 3 is an enlarged detail, partly in section, illustrating the anchorage for the gauge wire;

Fig. 4 is a detail view, partly in section, illustrating the pivotal connection between two sections of the gauge wire; and

Fig. 5 diagrammatically illustrates one of the gauge wires operating in a loom of the single shuttle type for producing single ply fabrics, or double ply fabrics connected by pile forming yarns extending from one to the other with one section of the wire interposed between said fabrics.

As shown in Fig. 1, each gauge wire, according to the present invention, includes a section 1 which is adapted to be woven into a strip of fabric, at and adjacent the fell. A movable section 2 extends rearwardly from the fell, for rising and falling with the warp threads to form open sheds therewith for passage of the shuttle, the section 2 being pivotally connected at 3, in end to end relation, to the woven-in section 1. Pivotally connected at 4 to the opposite end of the shed-forming section 2, is an anchor section 5, said section 5 being connected, in end to end relation, to the section 2, making a complete jointed gauge wire composed of the succeeding sections 1, 2 and 5.

The rear end 6 of each anchor section 5 is broadened and provided with an elongated slot 7 for reception of a rigid anchor bar 8. The bar 8 has pivotal connection with a plurality of hook-like members 9 disposed at opposite ends of the bar and at spaced intervals therebetween,

if desired. The anchorage hooks 9 are connected to a permanently fixed anchorage 10.

Each hook 9 includes a shank portion 11 extending through the fixed anchorage bar 10. The shank 11 is encircled by a spring 12 disposed between the rear face of the anchorage 10 and an adjustable abutment 13 mounted on the rear end of the shank 11 of each hook 9.

As shown in Fig. 1, the anchorage section 5, 10 in the present instance, is composed of a single strip of metal folded upon itself, with the opposite ends 6, 6 of the strip placed in laterally abutting aligned relation to each other. The main body portions 14, 14 also lie in lateral abutting 15 relation to each other and form an eye or loop 15 at one end of the section 5 which is adapted to pass through a crescent shaped opening 16 formed in the rear end of the shed-forming section 2. The concaved edge 17 of the crescent shaped opening 16 bears against the flat surface on the inner side of the extreme end of the eye 15 of the anchorage section 5.

The shed-forming section 2 is longitudinally slotted inwardly from the crescent opening 16 to permit the widened eye-end 6 of one of the body portions 14 to be passed through the shed-forming section 2 in producing the loop or eye 15 in the anchorage section 5.

The opposite end of the shed section 2 is similarly connected at 3 to the woven-in section 1. The woven-in section 1 is composed of a single strip of metal folded upon itself to provide a suitable eye or loop 18 having the inner flat surface 19 of the extreme end of the loop bearing against and rocking on the concaved edge 20 of the crescent opening 21 forming part of the pivotal connection 3.

Each shed-forming section 2 is adapted to pass through an elongated eye 24 formed in a vertical longitudinally movable heddle wire 25. The eye 24 is formed by slitting the wire longitudinally and displacing one portion 26 in one direction and one or more adjacent portions 27 in the opposite direction, laterally with respect to the plane of the wire 25, a sufficient distance to provide for free relative movement of the gauge wire section 2 therein. The eye 24 is sufficiently long, with respect to the width of the gauge wire section 2, to permit free rocking movement between the two substantially in the common plane occupied thereby.

As shown in Fig. 2, the heddle wires 25 are connected at their opposite ends to upper and lower bars 28, 28, forming part of the heddle frames which are operated by suitable mechanism forming part of the loom, to produce the warp sheds for weaving of the fabric, it being understood that the warp threads pass through similar heddle wires carried by other heddle frames for movement with or in opposition to the movements of the heddle frames which control the gauge wires 25 of the present invention, for forming the open warp sheds.

Preferably, as shown in Fig. 2, the anchorage 65 8 for the gauge wire is located on a direct line (a) with the pivotal connection 3 between the sections 1 and 2 of the wire, in a median plane between the extreme positions (b) and (c) into which the shed-forming sections 2 are movable, 70 whereby the gauge wire is held under substantially uniform tension throughout its full angular movement.

Normally, in using the gauge wires of the prior art, the shed-forming section of the wire is secured by a pivotal connection directly to its con-

trolling heddle wire, as indicated at x in Fig. 2, and in the movement of the shed-forming section from one extreme position (c) to its other extreme position (b), the pivot (x) tends to move in an arc (y), throwing the pivot (x) out of the 5 normal plane of movement of the heddle wire to an extent substantially equal to that indicated at (z), thereby placing the heddle wire under a heavy lateral or transverse strain attending the slipping of the section 1 in the fabric, 10 it being necessary to place sufficient transverse strain on the heddle wire to overcome the friction of the woven-in section of the gauge wire to effect withdrawal thereof from the fabric.

In accordance with the principles of the present 15 invention, the heddle wires 25 are relieved of the above noted strain as a result of the shed-forming sections 2 passing freely through and rearwardly beyond the heddle wires 25 and being there connected by the anchor sections 5 to the 20 fixed anchorages 10. With the improved construction, as the heddle wires 25 are raised and lowered, there is a pivotal sliding movement between the two, the ends of the slot or eye 24 producing the pivotal movement of the section 2 with 25 respect to the section 1, while at the same time permitting longitudinal movement of the section 2 through the eye 24, by which the lateral or transverse strain on the heddle wire is eliminated.

As the relative movable sections of the gauge 30 wire pass from the extreme position (b) to the extreme position (c), and vice versa, through the median position (a), causing a lengthening and shortening of the distance between the points 3 and 8 along the line (a), the springs 12 will 35 yield and retract accordingly, during such changes of distance between the two points, and maintain a substantially constant uniform tension on the gauge wires.

The rocking motion between the concaved 40 edges 17 and 20 of the crescent openings 16 and 21, in the opposite ends of the section 2, with respect to the flat surfaces formed on the inner surfaces of the loops 15 and 18 of the sections 1 and 5 respectively, eliminates wear at the pivots 45 between said sections and lengthens the useful life of the wires.

I claim:

1. A gauge wire for cooperative association with a control heddle in weaving fabrics, said gauge 50 wire being composed of two end sections and an intermediate section pivotally connected in end to end longitudinal succession, one end section being adapted to be woven into the fabric and to be slipped longitudinally therein and with respect thereto, the intermediate section being adapted to pass through an elongated eye in the heddle to provide a pivotal and transversely slideable connection with said heddle, and means for anchoring the second end section against substantial longitudinal movement to effect said slippage of the opposite end section and relieve said heddle of attending transverse strains.

2. A gauge wire for cooperative association with a control heddle in weaving fabrics, said gauge 65 wire being composed of two end sections and an intermediate section pivotally connected in end to end longitudinal succession, one end section being adapted to be woven into the fabric and to be slipped longitudinally therein and with respect thereto, the intermediate section being adapted to pass through an elongated eye in the heddle to provide a pivotal and transversely slideable connection with said heddle, and resilient means for anchoring the second end section against sub- 70 75

stantial longitudinal movement to effect said slippage of the opposite end section and relieve said heddle of attending transverse strains.

3. A gauge wire for cooperative association with a control heddle in weaving fabrics, said gauge wire being composed of two end sections and an intermediate section pivotally connected in end to end longitudinal succession, one end section being adapted to be woven into the fabric and to be slipped longitudinally therein and with respect thereto, the intermediate section being adapted to pass through an elongated eye in the heddle to provide a pivotal and transversely slidable connection with said heddle, and means for anchoring the second end section against substantial longitudinal movement to effect said slippage of the opposite end section and relieve said heddle of attending transverse strains, said anchorage comprising a rigid bar for connection with a plurality of said gauge wires in side by side relation along said bar to effect simultaneous uniform slippage of the woven-in ends of said plurality of gauge wires.

4. A gauge wire for cooperative association with a control heddle in weaving fabrics, said gauge wire being composed of two end sections and an intermediate section pivotally connected in end to end longitudinal succession, one end section being adapted to be woven into the fabric and to be slipped longitudinally therein and with respect thereto, the intermediate section being adapted to pass through an elongated eye in the heddle to provide a pivotal and transversely slidable connection with said heddle, means for anchoring the second end section against substantial longitudinal movement to effect said slippage of the opposite end section and relieve said heddle of attending transverse strains, said anchorage comprising a rigid bar for connection with a plurality of said gauge wires in side by side relation along said bar to effect simultaneous uniform slippage of the woven-in ends of said plurality of gauge wires, and resilient means connecting said bar to a rigid support at predetermined points along the length of said bar.
